(57) **CLAIM**

The ornamental design for a pump for liquids, as shown and described.

DESCRIPTION

1 Pump for liquids

1.1 : is a top view;

1.2 : is a front view;

1.3 : is a left side view;

1.4 : is a perspective view;

1.5 : is a second perspective view;

1.6 : is a third perspective view; and

1.7 : is a fourth perspective view.

The portion of the article shown in broken lines form no part of the claimed design.

1 Claim, 7 Drawing Sheets(56)
